D. F. CURTIN

LINER FOR SANITARY SODA HOLDERS

Filed Jan. 3, 1921

UNITED STATES PATENT OFFICE.

DAVID F. CURTIN, OF CHICAGO, ILLINOIS.

LINER FOR SANITARY SODA HOLDERS.

Application filed January 3, 1921. Serial No. 434,446.

To all whom it may concern:

Be it known that I, DAVID F. CURTIN, a citizen of the United States, and a resident of the city of Chicago, in the county of Cook and State of Illinois, have invented certain new and useful Improvements in a Liner for Sanitary Soda Holders; and I do hereby declare that the following is a full, clear, and exact description of the same, reference being had to the accompanying drawings, and to the numerals of reference marked thereon, which form a part of this specification.

This invention relates to an improved liner for soda holders especially those of interior conical form such as are shown and described in Letters Patent to David F. Curtin, Nos. 1,189,018 and 1,303,171, patented on May 11th, 1915, and May 6th, 1919, respectively. It will also be understood that this liner is adapted to be used with any form of holder of similar conical shape on the interior thereof.

The chief object of this invention is the provision of a liner for sanitary soda holders which can be manually inserted therein without any previous shaping of the same into the form of a cup and which, when inserted, will be non-leakable.

A further object of the invention is the provision of a liner for sanitary soda holders which can be shipped to the consumer or dealer in a flat form and made into the shape of a cup by him at his convenience or whenever necessary.

Another important object of this invention is the provision of an improved liner for sanitary soda holders which will provide a non-leakable cup when inserted therein without the use of any adhesive and without any preliminary formation of the cup.

Still another important object of this invention is the provision of a liner for sanitary soda holders which when formed into the shape of a cup and inserted into a holder is held therein and in close contact with the side thereof by means provided on the holder so that there will be no liability of the liner to tend to assume its original flat shape or spring up out of the holder.

Other and further important objects of the invention will be apparent from the disclosures in the drawings and annexed specification.

In the drawings:

Figure 1 represents a blank from which

the improved liner is made showing the position of the cup thereunder in dotted lines.

Figure 2 is a top view of the blank showing the same after it has been pushed part- 60 way into the cup.

Figure 3 is a side elevation showing the assembled holder and liner.

Figure 4 is a top plan view of the cup showing the liner in place therein. 65

Figures 5 and 6 are side and front elevations, respectively, of the shaped liner.

Figure 7 is an elevational detail of the latch.

Figure 8 illustrates a storage holder containing a number of formed paper cups. 70

As shown on the drawings:

The reference numeral 10 indicates a blank of approximately triangular shape having one of its edges or sides 11 in the form of an 75 arc of a circle. The other two edges are shorter but of equal length to each other and are slightly concave, and they terminate in rounded projections or tabs 12 adjacent each other and separated merely by means 80 of a slit 14 in the blank.

The termination of the slit 14 marks the exact center of the circle, one arc of which forms the edge 11 of the blank and this point forms the apex of the cup when the 85 same is formed into a liner for a holder.

The blank is preferably made of paper, coated with paraffine or some other waterproofing substance, and is manually inserted into the holder 16 which is preferably of 90 the shape shown in Figure 3 but may be of any conical form and may even be in the form of an open dish like those ordinarily used to serve sundaes and the like.

In operation, in putting the liner into the 95 holder the same is placed flat on the top edge of the cup in the position shown in Figure 1, the relation of the circular edge of the cup to the blank being shown in the dotted lines with the end of the slit 14 at the 100 edge of the cup. The blank is then pushed down into the cup by means of the fingers of the operator or by any convenient instrument, the end of the slit 14 being kept against the inside of the holder and the 105 liner gradually assumes the shape shown in Figure 2, the two tabs 12 overlapping each other to form an apex at the termination of the slit 14. After the liner has been fully inserted into the cup and with its shape corresponding to the interior thereof it assumes 110 the position shown in Figures 4, 5 and 6 in

which position it is adapted to receive a soda or the like and will maintain the same in the holder without any possibility of leakage, the weight of the liquid being sufficient to press the liner against the sides of the cup and to hold the overlapping edges together with sufficient pressure to prevent the escape of any liquid therethrough. The apex of the cup is doubly protected against leakage by means of the overlapping tabs 12 which encircle each other for approximately two entire revolutions thereby forming a double reinforcement at the bottom point of the cup which would ordinarily be the part most likely to leak.

As the blank or liner is originally in a flat form there will be a tendency for the same to reassume said flat form and to spring upward out of the cup after having been pushed or positioned thereinto. In order to prevent any such upward movement before the soda or liquid has been placed into the cup, a latch 18 is provided preferably positioned in close relation to the handle of the cup as shown in Figure 3. This latch is provided with any preferable adjustable retaining means 20, which may consist of a frictional binding screw entering a slot 21 in the latch member, and by slightly loosening the screw the latch can be slid up or down as is obvious.

It will be obvious that the liner retaining means or latch 18 need not be positioned adjacent the handle, but may, if desired, be attached at any point on the periphery of the rim of the cup. In fact any holding means that will serve to retain the liner in adjusted position will suffice. For example, a latch may be placed in the base of the holder which is provided with an opening through which the apex of the liner extends said opening being primarily for the purpose of preventing any foreign matter from accumulating in the apex of the holder and thereby preventing the proper seating of the liner therein. Such a latch placed in the base of the holder and adapted to grip the protruding apex of the liner and retain it in position may in some cases be preferred, being entirely concealed from view.

It will be evident that if a liner is inserted into a holder when required and a beverage immediately placed therein, the liner could and preferably would be held in position in the holder for a short time by means of the thumb of the dispenser of the beverage. However, when a number of cups are to be filled at substantially the same time, the latches 18 constitute a valuable addition as they serve to retain the liners in position in the cups and hold the same ready for the dispensing of a number of beverages.

The liners may be singly inserted into the holders as needed, or, if desired, a number

of liners, approximately five or six, may be inserted into one holder at the same time and formed roughly into shape. This may be repeated several times so that a number of liners according to the estimated requirements may be roughly shaped and ready in order to be quickly positioned into holders when needed. These liners after being roughly shaped in the manner described may be stacked or nested in a storage holder 22 as shown in Figure 8, which may be similar to the ordinary paper cup holder, and a conical weight 23 may be inserted in the upper portion of the holder to fully shape, expand and hold the same nested in expanded form.

It will be seen that herein is provided a liner for sanitary soda holders which can be used as readily as the prepared conical cups now on the market and which can be manufactured in greater quantities, and which moreover can be shipped in flat form, thereby effecting a saving of space and freight charges. The peculiar shape of this blank constitutes a very valuable feature inasmuch as it has been found to be the most practical shape which will result in the formation of a conical liner which will be positively non-leakable when inserted into a holder and filled with a beverage of any sort. It will further be seen that there is no possibility of any puncturing of the liner as the same is at all times held securely against the interior of the cup which reinforces and protects the same from any accidental openings or punctures being made by spoons or the like.

I am aware that many changes may be made and the details of construction varied through a wide range without departing from the principles of this invention, and I therefore do not purpose limiting the patent granted hereon, otherwise than necessitated by the prior art.

I claim as my invention:

1. A blank for forming a liner for a sanitary soda holder, said blank being substantially triangular in shape and having one of its sides in approximately the arc of a circle and the other two sides of substantially equal length to each other and corresponding closely to radii of said circle but being slightly curved inwardly and ending in adjacent tabs separated by a slit which extends to the center of the circle upon an arc of which the first side is formed.

2. A blank for forming a liner for a sanitary soda holder, said blank being adapted to automatically assume a conical shape when pushed into a holder.

3. A cup for dispensing beverages comprising in combination, a holder of interior conical shape, and a liner adapted to automatically assume the shape of said holder when pushed therein, and slidable means on

the holder adapted to retain the liner in position.

4. A cup for dispensing beverages comprising in combination, a holder of interior conical shape, and a liner adapted to automatically interfit said holder when placed therein, and slidably adjustable means on the holder adapted to hold the liner from springing from said holder, said liner being so constructed as to nonleakably retain a liquid without the use of any adhesive for binding the edges thereof together.

5. A liner for sanitary soda holders adapted to be curled upon itself as it is pushed into the holder.

6. A cup for dispensing beverages comprising in combination, a holder, a liner adapted to automatically interfit said holder when placed therein, and a slidably hooked member on the holder adapted to retain the liner in position.

7. A cup including a conical holder having its large end open, in combination with a lining of water-proof material having sectors of identical size and form overlapped to shape the material to accurately and resiliently fit into said holder.

8. A cup including a conical holder having its large end open, in combination with a lining formed of water-proof material having inclined converging sectors of identical shape adapted to be overlapped and curled to shape the material to accurately fit into said holder, slidable means upon said holder adapted to engage said lining and retain the same in position in the holder, and a set screw for holding said slidable means locked in adjusted position.

9. A cup including a conical holder, in combination with a lining formed from a water-proof blank having sectors loosely overlapped to temporarily shape said blank to accurately fit into said holder, slotted means slidably engaged upon said holder adapted to engage the formed blank and retain the same in position in the holder, and a set screw projecting through the slotted means and engaged in the holder to hold the slotted means locked in adjusted position.

10. The process of making conical paper cups consisting of cutting a proper blank on substantially the arc of a semi-circle,

with inclined converging portions rising from the ends of the arc, and a slit dividing said inclined portions and then pressing said blank into a conical holder to form the cup.

11. The process of making conical paper cups consisting of properly shaping and slitting a paper blank and pressing it into a conical holder whereby portions of the blank are forced to overlap one another and curl to form a conical cup with a reinforced apex.

12. A blank for forming conical paper cups comprising a member having a semi-circular portion with inclined converging portions rising from the ends of the arc and a slit dividing said converging portions and extending to the center of the point from which the semi-circular portion is struck.

13. A one piece sanitary cup liner blank comprising a semi-circular portion having tabs of similar form extending toward one another from the ends of the semi-circular portion.

14. The combination with a holder, of a cup blank adapted to be pushed into said holder and curl about itself to assume the shape thereof, and means on said holder to hold the shaped blank against springing upwardly out of said holder.

15. The combination with a holder, of a cup blank adapted to be pushed into said holder with overlapping portions of said blank springing outwardly toward the inner wall of said holder.

16. A cup for dispensing beverages comprising in combination, a holder, and a liner blank having projections thereon, said liner blank adapted to be pushed into the holder to cause said projections to cross one another and curl around the interior and exterior of the body portion of said liner blank to cause the same to form a liner to fit the holder.

In testimony whereof I have hereunto subscribed my name in the presence of two subscribing witnesses.

DAVID F. CURTIN.
